JEWELRY FINDING OR SIMILAR ARTICLE

Robert S. Grandy, 731 S. Vine St.,
Hinsdale, Ill. 60521

Filed Sept. 16, 1971, Ser. No. 163,115

Term of patent 14 years

Int. Cl. D11—01

U.S. Cl. D45—19 R

FIG.2

FIG.5

FIG. 1 is a front view of a jewelry finding or similar article showing my design;

FIG. 2 is a top edge view;

FIG. 3 is a right side view as seen from the left of FIG. 1;

FIG. 4 is a side view as seen from the right of FIG. 1;

FIG. 5 is a bottom view thereof.

The back of the jewelry finding or similar article of my design is not shown and is plain and unornamental.

I claim:

The ornamental design for a jewelry finding or similar article, as shown and described.
